(57) **CLAIM**

The ornamental design for the set of earrings, as shown and described.

DESCRIPTION

FIG. 1 is a perspective view of the earring, showing my new design in a first embodiment;

FIG. 2 is a front view thereof;

FIG. 3 is a side view thereof, the other side being a mirror image;

FIG. 4 is a rear view thereof;

FIG. 5 is a perspective view of the earring, showing my new design in a second embodiment;

FIG. 6 is a front view thereof;

FIG. 7 is a side view thereof, the other side being a mirror image; and,

FIG. 8 is a rear view thereof.
